(57) **CLAIM**

The ornamental design for a compaction wheel cleat, as shown and described.

DESCRIPTION

FIG. 1 is a perspective view of a compaction wheel cleat in accordance with an embodiment of the present invention.

FIG. 2 is a side elevational view thereof;

FIG. 3 is a front elevational view thereof;

FIG. 4 is a top plan view thereof; and,

FIG. 5 is a bottom plan view thereof.

Any broken lines shown in all figures are for illustrative purposes only and form no part of the claimed design.
